UNITED STATES PATENT OFFICE.

HENRY M. VAN DEUSEN, OF WESTFIELD, MASSACHUSETTS.

MOP.

Application filed May 1, 1926. Serial No. 106,063.

This invention relates to a mop and more specifically, a reversible mop.

The principal object of this invention is to obtain a mop which will adjust itself to 5 any position.

The novelty lies in the mop having means whereby the surface may be reversed.

Other novelty lies in the simple construction.

10 Further novelty will be shown by the specification and drawing.

One sheet of drawing accompanies this specification as part thereof in which like reference numerals indicate similar parts 15 throughout.

Figure 1 is a top plan with a section of the mop removed showing the construction and.

Figure 2 is a side elevation.

20 In accordance with my present invention 1 represents a mop head comprising mop strands 2, mounted in a frame 3 consisting of twisted wires, having a rod 4 running transverse the frame 3. Attached at the 25 outer ends of rod 4 are brackets 5 fastened to handle 6 by any well known means. At the outer ends of rod 4 are rubber pads 7 to prevent scratching or marring of wood-work when the mop comes in contact with 30 said woodwork.

As actually manufactured the two wires comprising the frame 3 are twisted so as to embrace mop strands 2 within the loop formed between the twist in the wires, each 35 twist forming a node and a fastening means

to hold the mop strands in place. The mop head having been formed, it is then mounted on a transverse rod 4 which passes between the two wires forming the frame to brackets 5 where it is pivotally mounted. 40

As actually used the mop head being reversible, the house wife can conveniently get into any shaped corner or awkward place and at the same time when one surface is used the mop may be reversed and a fresh 45 surface presented for use. The pads 7 prevent the scarring of woodwork or furniture when the mop is being used in inaccessible places.

Having thus described my invention what 50 I claim is:

A mop comprising a handle, forked brackets secured on opposite sides of said handle near one end thereof and extending in opposite directions laterally therefrom, a 55 ring formed of a plurality of strands of wire twisted around each other and having mop material secured between said strands by the twisting thereof, a rod passing diametrically through said ring between the 60 twisted strands thereof and rigidly fixed thereto and having its apposite ends projecting through said ring and pivoted in the free ends of said brackets, said ring and material being freely rotatable with said rod 65 in either direction through the space between said brackets.

In testimony whereof I affix my signature.

HENRY M. VAN DEUSEN.
